UNITED STATES PATENT OFFICE.

NATHAN H. SUREN, OF NEEDHAM, MASSACHUSETTS, ASSIGNOR TO THE GAMEWELL FIRE ALARM TELEGRAPH COMPANY, OF NEWTON UPPER FALLS, MASSACHUSETTS, A CORPORATION OF NEW YORK.

FIRE-ALARM SYSTEM.

Application filed July 11, 1919. Serial No. 310,159.

To all whom it may concern:

Be it known that I, NATHAN H. SUREN, a citizen of the United States, and a resident of Needham, in the county of Norfolk and Commonwealth of Massachusetts, have invented an Improvement in Fire-Alarm Systems, of which the following description, in connection with the accompanying drawings; is a specification, like characters on the drawings representing like parts.

This invention relates to fire alarm systems and more particularly to auxiliary fire alarm systems whereby signalling mechanism in the main circuit is adapted to be actuated from one or more stations on an auxiliary circuit.

One object of the invention is to render the system immune from the transmission of false signals through the occurrence of a line fault such, for example, as an accidental break in the auxiliary circuit.

This and other objects of the invention will be best understood by reference to the following description when taken in connection with the accompanying illustration of one specific embodiment thereof, while its scope will be more particularly pointed out in the appended claims.

In the drawings,—

Fig. 1 shows more or less diagrammatically the front elevation of a usual type of street fire alarm box to which is applied one specific form of box pulling attachment which may be used in carrying out the invention.

Fig. 2 is a sectional elevation on the line 2—2 in Fig. 1, looking in the direction of the arrow there shown, the main drum being also shown in section.

Fig. 3 is a sectional elevation taken on the line 3—3 in Fig. 2 looking in the direction of the arrow, or from the opposite side from Fig. 1, and showing the escapement and ratchet.

Fig. 4 is a sectional plan view taken on the line 4—4 in Fig. 1 and showing the releasing magnet and its armature.

Fig. 5 is a diagram showing the circuit arrangement of an auxiliary circuit and its relation to the main line and the main line box.

Figs. 6, 7 and 8 are diagrams showing the connections and direction of current flow in the auxiliary circuit and the magnet windings in different positions of the circuit changing devices at one of the auxiliary signalling stations.

Referring to the drawings, and particularly to Figs. 1 and 5, I have shown, conventionally and for illustrative purposes, a main fire alarm circuit 10, passing through the central station 11 and including thereat a battery or other source of current 12.

Included in the main line circuit there are also provided one or more signalling stations at which there are located suitable signalling boxes or mechanisms, including each a signalling train, one of such stations being indicated at 13 (Fig. 5) and others at 14 and 15, and each one being adapted, when actuated, to transmit to the central station its individual characteristic signal.

The signalling box at the station 13 (Fig. 1) has the casing 17 within which there is contained any of the usual or suitable signalling mechanism. The specific construction of this apparatus is immaterial, but, as typifying a usual mechanism of this kind, I have herein indicated conventionally and diagrammatically the working parts of a common form of signalling train which is adapted to be released and set into operation to transmit its signal by the depression of the starting lever 18. The latter may be operated by any of the usual manual pull devices. The pull lever may be depressed and the train released by the bell crank trip lever 19. The lower end of the latter bears against the upper edge of the lever 18, while its upper arm is jointed to the box tripping link 20, which latter is adapted to be pushed to trip the box by the auxiliary magnet 21 acting through suitable mechanism, to be hereinafter described.

The controlling or auxiliary magnet 21, at each main line box, is under the control of an auxiliary line extending from the main line box over any desired territory and having one or more emergency signalling stations (Fig. 5) 22, 23, 24, etc., arranged at intervals and each provided with a signalling device, herein typified by the manually

operated pull switch 25, by means of which, as will be described, the main line box may be actuated and the characteristic signal of that box transmitted to the central station.

5 In the illustrative embodiment of the invention, the auxiliary line is normally closed and energized by the current flow therein, such current being preferably derived from the main line circuit. In the preferred form 10 of the invention, the auxiliary line circuit is in series with the main line circuit.

In the illustrative embodiment of the invention also the controlling devices are preferably so constructed that the box 15 starting magnet is not affected either by the passage of the auxiliary line current which persists while the system is in its normal condition, or by interruption of such current which might follow an accidental break 20 in the auxiliary circuit, so that the main line box signal will not be transmitted to the central station through any interruption of the current in the auxiliary line, and the only way in which such signal can be 25 transmitted is through the movement of the switch 25 at the auxiliary signalling station, as hereinafter described.

While this result may be secured through 30 various other specific arrangements, in the illustrated arrangement the magnet 21 is provided with similar and substantially equal differential windings 30 and 31. In one position of the switch 25, these windings 35 are arranged in opposition to each other—thereby one largely or wholly neutralizing the magnetizing effect of the other and rendering the magnet ineffective for starting the box—while in another position of the switch 25 the windings are arranged to reinforce one the other, thereby adding the magnetizing effect of one to that of the other and becoming effective to energize the magnet and start the box.

To this end the auxiliary line comprises 45 a plurality of loops in series with the main line circuit and with each other, said loops being also in series with the magnet windings and one of the latter—herein the winding 31—being located between the two loops. Through the circuit changing switches 25 the connections between the loops of the auxiliary circuit may be changed at any 50 emergency signalling station so as to change the direction of the current through the intermediate magnet winding, thus adding the effect of one to the other and starting the box.

60 Referring now to the electrical connections (Fig. 5), the main line circuit is connected to the terminals 32 and 33 at the main line box, the circuit leading from the terminal 32 through the conductor 34, the non-interfering magnet 35 and the normally closed signalling contacts 36 to one

of the windings 30 of the differentially wound magnet 21, and thence to the box terminal 37. The companion winding 31 on the magnet 21 is connected between the box terminals 38 and 39. The auxiliary line circuit includes the conductors 40, 41, 42 and 43, connected respectively to the box terminals 33, 37, 38 and 39 and leading therefrom to the nearest auxiliary signalling box 22.

The wire 43 at the station 22 is connected 75 to the terminal 44 and, when the switch is in its normal position, this in turn is connected to the terminal 45 and thereby to the conductor 43^a which extends to the next adjacent signalling station 23, whereat there is a similar arrangement of connections, the conductor 43^a being connected to the conductor 43^b leading to the next signalling station 24. A similar arrangement is provided at each of the succeeding 80 signalling stations until, beyond the last, (herein station 24) the conductor 43^c is connected directly to the conductor 40 which extends back through stations 23 and 22 to the terminal 33 at the main line box. 90 In the normal positions of the several circuit changing devices 25, therefore, the conductor 40 combined with the conductors 43, 43^a, etc., constitute a loop between the main line box terminals 33 and 39 and passing 95 through the successive auxiliary signalling stations.

By a series of connections similar to the connections 43, 43^a, etc. the conductors 41 and 42 are connected normally in a loop 100 circuit which passes through the successive signalling stations, the conductors 41 and 42 being connected respectively at the station 22 to the conductors 41^a and 42^a, and the latter at the station 23 respectively to the conductors 41^b and 42^b, and the latter at the station 24 to the conductors 41^c and 42^c, which latter are permanently connected together beyond the station 24.

In Fig. 6 there is represented the current 110 flow through the several conductors, when normally connected by the switches as shown in Fig. 5. It will be seen that the current entering from the central station at the box terminal 33 passes through the auxiliary circuit along the conductor 40 to the end of the circuit, thence back through the successive stations through conductors 43^c, 43^b, etc., to the main box terminal 39, thence through the magnet windings 31 to the terminal 38, and thence again through each successive signalling station through conductors 42, 42^a, etc., and back again through the successive conductors 41^c, 41^b, etc., to the terminal 37. Thence it 120 passes through the second differential winding 30 and through the signalling contacts 36, the magnet 35 and conductor 34 to the 125

box terminal 32. Under these conditions the direction of current flow through the two windings is opposed as indicated in Fig. 6, leaving the magnet de-energized and 5 ineffective.

When it is desired to send a signal from one of the auxiliary stations, as for example the station 22, the pull switch 25 is moved to the dotted line position therein shown, 10 in virtue of which the terminal 44 becomes connected directly to the terminal 48, the terminal 46 to the terminal 49 and the terminal 47 to the terminal 50. The terminal 48 at the switch 22 is permanently connected 15 to the terminal 50 by the conductor 51, so that this position of the switch connects the conductor 43 to the conductor 41. The terminal 49 is connected to the conductor 40 through the conductor 52, so that 20 in this position of the switch the conductor 42 is connected directly to the conductor 40. This establishes a circuit relation which is diagrammatically shown in Fig. 8, the auxiliary line circuit being then broken 25 beyond the station 22, or beyond the station from which the signal is sent, and consists of two loops comprising the circuits 40 and 42 on the one hand, and 41 and 43 on the other. This reverses the direction of the current 30 flow through the intermediate winding 31, the current flow being through the conductor 40 back through the conductor 42 and through the winding 31 in a reverse direction from what it was before, thence through 35 the conductor 43 back to station 22 and thence back to the main line box through the conductor 41 and through winding 30 in the same direction as before. The cumulative effect of the two windings secured by 40 this establishment of circuits energizes the magnet and starts the box.

The circuit connections at each signal station may be substantially the same as that already described, requiring no further description, it being obvious that the pulling of the switch at either the station 23 or 24, or any succeeding station which may be employed, effects a cross-connection between the two loops of the circuit similar to that already described, reversing the current and pulling the box.

In order that a break in the auxiliary circuit may not incapacitate the signalling stations located between the break and the main line signal box from functioning until such time as the break is repaired, I have provided means whereby the loop circuits on the auxiliary line which include the break may be reestablished or short-circuited so that they remain intact up to and including the signalling station next preceding the point where the break has occurred. While such short-circuiting apparatus might be embodied in a separate switch, herein the 55 switches 25 are so constructed that they may

be pulled from either the normal starting position shown in Fig. 5 or from a second starting position in which all succeeding stations are cut out of circuit. Such a circuit relation is shown diagrammatically in Fig. 70 7 where it may be assumed that a break has occurred between station 22 and station 23, and the pull switch 25 at station 22 has been set to be pulled from its secondary starting position. In the normal position of the 75 switch 25, the latter is retracted by a spring 54 against a stop pin 55, the switch being pulled from such starting position to the dotted line position as hereinbefore described. If a break occurs between stations 80 22 and 23, the switch 25 at station 22 is reset to start from the intermediate contacts 56, 57 and 58 being retracted against a stop pin 59 which is temporarily employed to limit the retractile movement of the switch 85 when released. The contact 56 is connected to the contact 49 by the conductor 60 and the contact 57 with the contact 58 by the conductor 61, so that, when the switch is set at the secondary starting position, the loop circuits 90 40 and 43 on the one hand and 41 and 42 on the other are maintained through the station 22 as before, the succeeding stations beyond the break being cut out. Obviously, if the break occurs beyond any of the succeeding 95 stations, the circuit beyond such station may be cut out in a similar way and the integrity of the loop circuits through all the preceding stations may be maintained as before.

Referring now to the devices which are actuated by the starting magnet (Figs. 1 and 5), the latter and its associated parts are mounted upon a segmental frame or casing 70, secured to the side of the casing 17 and presenting supporting frame members 71 105 and 72 in which a main shaft 73 (see Fig. 2) is journaled.

A motive device for starting the box is provided in the form of the main drum 74, loosely mounted on the shaft but connected 110 thereto by means of a flat coil spring 75, one end of which is secured to the interior of the drum and the other end to a hub 76 upon the shaft. The apparatus is placed in its "set" condition, as will more fully appear, 115 by turning the shaft 73 through a suitable turning key applied to the squared end 77 of the shaft, thereby winding up or tensioning the spring 75. The shaft 73 has fixedly secured to its end a hub 78 carrying the ratchet 120 79, engaged by the spring pressed pawl 80, pivoted to the frame member 72, so that the shaft is prevented from turning in a counter-clockwise direction, as viewed in Fig. 3, and compelling the drum, when released, to turn 125 in a clockwise direction as viewed in Fig. 3 or a counter-clockwise direction as viewed in Fig. 1.

The drum, however, is normally held 130

against turning movement, by suitable releasing mechanism which is set into operation by the energization of the starting magnet 21. Referring to Figs. 2 and 3, the drum is provided at one circumferential edge with the gear 84, adapted to mesh with the pinion 85, connected to the pallet wheel 86 on the pallet wheel shaft 87, the pallet wheel having engaged therewith the pallet 88, of such construction that the drum in its rotation is given a retarded or time-controlled movement. The pallet wheel and drum are normally held against movement by a stop pin 89, having a flattened side carried by the releasing or trip lever 90, the latter pivoted at 91 upon the frame member 72. The stop pin 89 on the lever normally engages a similar but oppositely faced pin 92 on the pallet wheel 86, holding the latter, and likewise the drum against turning.

When the releasing or trip lever 90 is moved to a position of release by the armature lever, as hereinafter described, it moves it against the retractile tension of the spring 93 and carries the stop pin 89 out of the path of the pallet wheel pin 92. The pallet wheel thereupon starts to revolve, releasing also the drum 74 which is geared thereto. This permits the pallet wheel to make one full revolution before being brought to rest by the stop pin 89, on the releasing lever, which latter moves back to the stop position shown in Fig. 3 on the de-energization of the magnet 21. The drum is geared to the pallet wheel by reduced gearing so that during the rotation of the pallet wheel the drum makes substantially one quarter of a revolution.

To release the trip lever, the lower end of the latter is adapted to be engaged by the laterally projecting pin 95, carried by one end of the armature lever 96 on the upper end of the armature shaft 97 and adapted to oscillate therewith when moved by the armature 98, connected to the lower end of the armature shaft (Figs. 1 and 4).

When the starting magnet is energized, the armature is attracted toward the magnet poles 99, against the tension of the retractile spring 100, turning the armature shaft and simultaneously swinging the armature lever 96, the pin 95 being thereupon brought into engagement with the lower end of the releasing lever 90, forcing the stop pin 89 out of the path of the pin 92 on the pallet wheel.

As soon as the drum 74 starts to turn, it acts to depress the box-starting lever 18 and start the box. To this end, the link 20 is jointed to an actuating lever 105, pivoted at 106 on the frame piece 70 and normally held in an inactive position by the coiled torsion spring 107, secured to the lever at its pivot. The upper end of the

lever 105 carries a laterally extending pin or cam roll 108, which engages the edge 109 of internal cam 110, secured to the adjacent side of the drum 74. The cam has four similar successive edge formations which act upon the cam roll 108, when the drum is turned clockwise (in Fig. 1) for a quarter of a revolution, to move the cam roll radially inward and swing the lever 105 counter-clockwise (as seen in Fig. 1), this serving to depress the starting lever 18 and start the box.

When the pallet wheel has completed its revolution and is again brought to rest, the drum 74 has turned one quarter of a revolution permitting the cam roll to be moved back by the torsion spring 107 into the shouldered recess of the next adjoining formation of the face cam, and leaving the actuating lever and other parts in the normal position corresponding to that shown in Fig. 1.

The main line box is then ready to be again started by a signal received from the same auxiliary line box, or from any other box on the auxiliary line. If desired, the spring 75 may be sufficient to permit the box to be pulled any desired number of times without the necessity of re-winding, thus permitting the box to be pulled under the control of the auxiliary circuit a plurality of times without resetting.

The signalling switches 25 at the auxiliary station are merely conventional representations of any well-known devices which preferably provide as soon as actuated for a certain movement of a circuit changing member, which member is automatically self-restoring and moves with certainty to its initial starting position after a short but appreciable interval.

It will be seen that this box starting attachment may be applied to the ordinary existing fire alarm boxes without affecting or interfering with their manually operative capacities. In the specific arrangement herein illustrated, it will also be seen that due to the differentially wound magnet, both windings of which are in series with the main line, only the intended circuit change at the auxiliary station can serve to start the main line box. Any accidental break in the auxiliary circuit serves merely to de-energize the magnet and stop the main line current flow.

While I have herein shown and described for purposes of illustration one specific embodiment of the invention, and have illustrated the same in connection with a normally closed auxiliary circuit, employing the main line current, and in series to a box starting magnet, the invention as to many of its features is not limited to that particular application, but is capable of a great variety of uses and is not limited to the

form or relative arrangement of parts by which the same has been herein disclosed for purposes of illustration.

Claims:

5. 1. In a fire alarm system a main line circuit having a central station and one or more main line signalling boxes, each with a box starting attachment and a magnet having differential windings for actuating said attachment, an auxiliary line with one or more signalling stations having circuit changing devices for controlling the box starting attachment through said magnet, said auxiliary line normally having a current therein 70 and comprising a plurality of loops in series with the main line and each other and in series with said differential magnet windings and normally connected at said auxiliary signalling stations to place said windings in opposition thereby rendering said magnet ineffective to start said box, either in the normal position of said circuit changing devices or in the event of a break in said auxiliary circuit, said circuit changing devices, 75 however, being effective when moved to one position at any auxiliary station to so connect said loops as to change the direction of current through one of said differential windings, adding the magnetizing effect of one to the other, thereby actuating said box starting attachment and transmitting the box signal to said central station. 80
2. In a fire alarm system having a central station and one or more main line signalling boxes, an auxiliary line in series with the main line and having one or more signalling stations with circuit changing devices thereat for controlling the main line signalling box, controlling means at the main line box including a differentially wound starting magnet having its differential windings connected to respond to the action of said circuit changing devices in the auxiliary line, but having connections to said auxiliary line rendering its magnet unresponsive to the interruption of current flow in said line, and means controlled by such responsiveness of said magnet to cause transmission of the main line box signal to the central station. 85
3. A fire alarm system having a main line box starting attachment including a differentially wound magnet, an auxiliary controlling line including circuits controlling the current flow through said differential windings and normally rendering said windings ineffective to start the box whether the auxiliary line is intact or broken and circuit changing devices on said auxiliary line 90 adapted to cause the current in said windings to flow in the same direction or in opposite directions. 95
4. In a fire alarm system a main line having a central station, one or more main line signalling boxes, an auxiliary line normally 100
- having a current therein and energized from the main line current source, one or more signalling stations having circuit changing devices for controlling a main line signalling box and controlling means responsive to the actuation of circuit changing devices at an auxiliary station to cause transmission of the main line box signal to the central station, but ineffective to cause transmission of such signal on interruption of current flow in such auxiliary line, said auxiliary station or stations being provided with means to cut out succeeding stations on the auxiliary line in the event of a break in said line beyond said station. 105
5. In a fire alarm system, a main line starting box having auxiliary starting mechanism, including a starting magnet with normally opposed differential windings, an auxiliary line circuit in series with the main line and said differential windings and a circuit changing device in said auxiliary circuit adapted to cause said windings to reinforce one the other in their magnetizing effect and start the box. 110
6. A box starting attachment for a manually operable main line starting box, comprising trip mechanism and a differentially wound magnet having its windings normally opposed one to the other, an auxiliary line having a plurality of circuits in series with the main line and with the windings of the magnet, and one or more circuit changing devices in said auxiliary circuit adapted to change the circuit and cause said windings 115 to reinforce the other. 120
7. An auxiliary box starting attachment for a main-line, fire-alarm box controlled through an auxiliary line, the auxiliary line being adapted to be energized from main line current energy characterized by the employment of tripping mechanism, a differentially wound magnet controlling the same, connections for the auxiliary line whereby the windings of the magnet may be connected either in opposing or assisting relationship but ineffective to start the box whether current is passing therethrough or whether the auxiliary line is broken, and a circuit changing device on the auxiliary line movable to place the magnet windings in assisting relationship. 125
8. An auxiliary box starting attachment for a manually operable main line fire alarm box, having an auxiliary starting magnet with differential windings normally in opposition, and an auxiliary line comprising a plurality of loops in series with the main line and each other and in series with the differential magnet windings, and circuit changing devices in said auxiliary circuit to cause said windings one to reinforce the other and start the box. 130
9. An auxiliary box starting attachment for a main line fire alarm box having trip 135

mechanism and a starting magnet with differential windings, an auxiliary line comprising a plurality of circuits in series with both sets of windings, and circuit changing devices for so governing the current paths in said circuits as to place said windings in either assisting or opposing relationship.

10. An auxiliary starting attachment for a main line fire alarm box having trip mechanism and a starting magnet with differen-

tial windings, an auxiliary line, said differential windings being in series with the main line, with the auxiliary line and with each other, and signalling means for reversing the relative direction of current flow in one of the windings.

In testimony whereof, I have signed my name to this specification.

NATHAN H. SUREN.
